(57) **CLAIM**

I claim the ornamental design for the awning head rod molding, as shown.

DESCRIPTION

FIG. 1 is a perspective view from the left front of the new design for the awning head rod molding;

FIG. 2 is a left side view thereof, with the right side view being identical thereto;

FIG. 3 is a front view thereof;

FIG. 4 is a rear end view thereof;

FIG. 5 is a top view thereof; and,

FIG. 6 is a bottom view thereof.

The claimed design has been broken on one end indicating indeterminate length.
